CLAIM

The ornamental design for an attachment for a vehicle wheel as shown and described.

DESCRIPTION

FIG. 1 is a perspective view of an attachment for a vehicle wheel showing my new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

In the drawings, the broken lines depict portions of the attachment for a vehicle wheel that form no part of the claimed design.
